UNITED STATES PATENT OFFICE.

JOHN R. MCGIFFERT, OF DULUTH, MINNESOTA, ASSIGNOR TO CLYDE IRON WORKS, OF DULUTH, MINNESOTA, A CORPORATION OF MINNESOTA.

LOG-LOADER.

No. 861,601.

Specification of Letters Patent.

Patented July 30, 1907.

Application filed December 28, 1906. Serial No. 349,832.

To all whom it may concern:

Be it known that I, JOHN R. MCGIFFERT, a citizen of the United States, and a resident of Duluth, county of St. Louis, and State of Minnesota, have invented a new and useful Improvement in Log-Loaders, of which the following is a specification, the principle of the invention being herein explained and the best mode in which I have contemplated applying that principle so as to distinguish it from other inventions.

10 My invention, relating, as indicated, to improvements in loading devices, has as its more immediate object the provision of a readily transportable log-loading machine. To this end it is concerned not so much with the character of the machine itself as with the means 15 devised for loading the same onto a vehicle in order to permit of its ready removal from one place to another, as may be demanded by the exigencies of the use for which it is intended.

Said invention, then, consists of means hereinafter 20 fully described and particularly set forth in the claims.

The annexed drawings and the following description set forth in detail certain mechanism embodying the invention, such disclosed means constituting, however, but one of various mechanical forms in which the principle 25 of the invention may be used.

In said annexed drawings: Figure 1 represents in side elevation one of the several types of loading machines employed in loading logs onto cars, together with a truck or car in combination with which such 30 loader is designed to be operated; Fig. 2 is an end elevation of such loader and car; while Fig. 3 includes respectively a plan view and side elevation of removable ways or rail-sections designed to be employed, in the manner hereinafter fully set forth, in effecting the 35 elevation of the loader onto such car when it is desired to prepare the former for transportation.

The type of loading mechanism chosen for the purpose of illustration in connection with my present invention comprises in the main simply a rectangular frame adapted to straddle a railway track and permit the passage therethrough over such track of the ordinary flat cars employed in logging operations, such frame being provided with an upper deck whereon is supported the usual hoisting mechanism and the like for 45 performing the operation of loading, for which the device is primarily intended. The construction of such loading mechanism being generally understood all parts thereof are here omitted save the winding drums for operating the several cables.

50 Having reference, then, to Figs. 1 and 2, it will be noted that A designates the upper platform or deck of the loader frame, which platform is supported upon four bow-like legs A' located near its respective corners. These legs are connected by lower longitudinal 55 bars, preferably channels, as shown, and the frame is

otherwise braced, in order to stiffen it against the shocks to which it is apt to be subjected in use, in any approved fashion. Journaled in suitable boxes a on the under side of the platform, near the respective ends of the frame, are two cross shafts B B, on the ends of 60 which are secured double flanged wheels b b. These flanged wheels extend downwardly a few inches below the lowermost part of the frame deck. Near one end of the platform or deck, the left one as shown in Fig. 1, is secured a spotting sheave C, while near the other 65 end of such deck is secured a block C'. A spotting cable or line C² from one of the drums c of the hoisting mechanism may be run over spotting sheave C alone, or over such sheave and block C' at the other end of the frame, as desired, or around such sheave and the block 70 C' at the other end of the frame.

In its normal position when in use for loading logs or the like onto cars, this machine straddles the track, as has been stated, the legs being bent inwardly, and resting upon shoes which are supported by the ties of 75 the track. The empty flat or logging cars can then be successively shoved or drawn between such legs and underneath the deck, the double flanged wheels b being raised a sufficient distance to amply clear the decks of such cars. When the machine is to be moved, 80 the loading frame or machine is elevated bodily on one of the cars in question in the following manner: Sections of rail D, Fig. 3, are mounted on the upper faces of timbers D' so as to slope downwardly at each end. These rail sections or ways are then placed longitudinally 85 on one of the flat cars so as to be in position to engage the aforesaid flanged wheels b when the car is drawn underneath the frame. The central and major portions of the respective rails D, which obviously lie parallel with the car deck, are sufficiently elevated 90 by the timbers D' upon which such sections are mounted to raise the loader-frame legs entirely off the ground or ties upon which their feet normally rest, when engagement is had with the flanged wheels b. In order to thus draw the car through beneath the frame, and 95 thereby elevate the latter thereon, the spotting line or cable C² already described is conveniently utilized. If the car upon which it is desired to load the frame stands behind the machine, that is, to the right as illustrated in Fig. 1, such spotting line is run over spotting 100 sheave C only, its free end being connected with the rear draw-head of the car. Obviously, upon winding in the line, the car will then be pulled forwardly underneath the frame with the result, as regards the elevation of the latter, previously noted. When, on the 105 contrary, the car which it is desired to utilize in the manner described, stands in front of the machine, the spotting line C² is passed both over sheave C and block C', and then forward to the other cross-head of the car.

In Fig. 1, the cable C², which is represented by a broken 110

line, is shown in both of these alternative positions. Suitable retaining means (not shown) are of course employed to prevent the frame from running off the ways or rail-sections when the car is put under motion.

The car illustrated in the drawings as being utilized to thus transport the loading machine, is an ordinary flat or logging car, as has been stated, upon which the ways or rail-sections D are only temporarily laid when it is desired to load the machine thereon. Obviously,

- 10 however, a special car may, if desired, be provided upon which corresponding rail-sections are permanently secured, and which may be provided furthermore with self-propelling mechanism, the method of loading the machine thereon being otherwise identical 15 with that described. Where a special car is thus employed, it may be run backwardly along the track and stand at the rear of the cars to be loaded, or such other disposition as may be feasible may be made of it instead. It is to the means which I employ for jacking 20 up or elevating the machine frame upon the transporting car, whatever the character of the latter, that I would here invite attention. My device is offered as being particularly a practical one for use in connection with heavy loading machines which are not required to be automobile, and ordinarily it is contemplated 25 that the use of the removable ways or track sections will be favored, for these can be carried along on the machine when not in use, and any ordinary car, by means thereof, can be converted on short notice into 30 a suitable truck for receiving the frame and transporting where it is desired.

Other modes of applying the principle of my invention may be employed instead of the one explained, change being made as regards the mechanism herein 35 disclosed, provided the means stated by the following claims or the equivalent of such stated means be employed.

I therefore particularly point out and distinctly claim as my invention:

- 40 1. In mechanism of the class described, the combination of a frame, a vehicle adapted normally to pass through and under said frame, and means adapted to be interposed between said frame and vehicle and to elevate the former upon the latter upon relative movement therebetween.
- 45 2. In mechanism of the class described, the combination of a frame, a vehicle adapted normally to pass through and under said frame, and a sloping member adapted to be interposed between said frame and vehicle and to elevate the former upon the latter upon relative movement therebetween.
- 50 3. In mechanism of the class described, the combination of a frame, a vehicle adapted normally to pass through and under said frame, and terminally inclined ways adapted to be interposed between said frame and vehicle and to elevate the former upon the latter upon relative movement therebetween.
- 55 4. In mechanism of the class described, the combination with a frame, of a vehicle, one of the same being provided with means adapted upon relative movement between said frame and vehicle to elevate the former upon the latter.
- 60 5. In mechanism of the class described, the combination with a frame, of a vehicle, one of the same being provided with a sloping member adapted upon movement with respect to the other to engage the latter, whereby said frame is elevated upon said vehicle.
- 65 6. In mechanism of the class described, the combination with a frame, of a vehicle, one of same being provided with terminally inclined ways and the other with means adapted to be engaged by said ways upon relative movement 70 between said frame and vehicle, whereby the former is elevated upon the latter.

7. In mechanism of the class described, the combination with a frame, of means for transporting the same, such means comprising a vehicle provided with a sloping deck adapted to engage and elevate said frame upon relative movement of said frame and vehicle. 75

8. In mechanism of the class described, the combination with a frame, of means for transporting the same, such means comprising a vehicle provided with a sloping deck adapted to engage and elevate said frame upon relative movement of said frame and vehicle, and means borne by said frame adapted to effect such movement. 80

9. In mechanism of the class described, the combination with a frame, of means for transporting the same, such means comprising a vehicle provided with a terminally sloping deck adapted to engage said frame and elevate the same upon said vehicle being drawn therebeneath. 85

10. In mechanism of the class described, the combination with a frame, of means for transporting the same, such means comprising a vehicle provided with a terminally sloping deck adapted to engage said frame and elevate the same upon said vehicle being drawn therebeneath, and means borne by said frame adapted to thus draw said vehicle. 90

11. In mechanism of the class described, the combination with a frame, of means for transporting the same, such means comprising a vehicle provided with a terminally sloping deck adapted to engage said frame and elevate the same upon said vehicle being drawn therebeneath, and means borne by said frame adapted to thus draw said vehicle beneath said frame from either end as desired. 95

12. The combination with a frame adapted to permit the passage of vehicles therethrough, and hoisting mechanism borne by said frame, of a vehicle provided with a sloping deck, said frame being adapted to engage such deck and be elevated thereby upon relative movement between said frame and vehicle. 105

13. The combination with a frame adapted to permit the passage of vehicles therethrough, and hoisting mechanism borne by said frame, of a vehicle provided with a terminally sloping deck, said frame being adapted to engage such deck and be elevated thereby upon relative movement between frame and vehicle. 110

14. The combination with a frame adapted to permit the passage of trucks therethrough, and hoisting mechanism borne by said frame, of a truck provided with terminally sloping ways, said frame being provided with means adapted to engage said ways upon relative movement between said frame and truck, whereby the former is elevated upon the latter. 115

15. The combination with a frame adapted to permit the passage of trucks therethrough, and hoisting mechanism borne by said frame, of a truck provided with terminally sloping ways, said frame being provided with means adapted to rotatably engage said ways upon relative movement 125 between said frame and truck, whereby the former is elevated upon the latter.

16. The combination with a frame comprising a deck and legs adapted to support the same, of hoisting mechanism borne by said deck, rotatable members mounted beneath the same, and a truck adapted to pass through between such legs and underneath said deck, said truck being provided with terminally sloping ways adapted to engage said rotatable members, and thereby elevate said frame. 130

17. The combination with a frame comprising a deck and legs adapted to support the same, of hoisting mechanism borne by said deck, rotatable members mounted beneath the same, and a truck adapted to pass through between such legs and underneath said deck, said truck being provided with removable terminally sloping ways adapted when properly disposed thereon to engage said rotatable members and thereby elevate said frame. 140

18. The combination with a frame comprising a deck and legs adapted to support the same over a track, of hoisting mechanism borne by said deck, wheels mounted beneath the same, and a car adapted to run on such track and to pass through between such legs and underneath said deck, said car being provided with terminally sloping rail-sections disposed to engage the wheels mounted beneath said deck and thereby elevate said frame. 145

19. The combination with a frame comprising a deck and legs adapted to support the same over a track, of hoisting mechanism borne by said deck, wheels mounted beneath the same, a car adapted to run on such track and to pass between such legs and underneath said deck, said car being provided with terminally sloping rail-sections disposed to engage the wheels mounted beneath said deck and thereby elevate said frame, and means connected with said hoisting mechanism for drawing said car underneath said deck. 5

20. The combination with a frame comprising a deck and legs adapted to support the same over a track, of hoisting mechanism borne by said deck, wheels mounted beneath the same, a car adapted to run on such track and to pass between such legs and underneath said deck, said car being provided with terminally sloping rail-sections disposed to engage the wheels mounted beneath said deck and thereby elevate said frame, a cable operable by said hoisting mechanism, and guiding pulleys disposed in said 0 frame so as to be adapted to guide said cable to pull said car thus underneath said deck from either end of the latter. 10

21. The combination with a frame comprising a deck and legs adapted to support the same over a track, of hoisting mechanism borne by said deck, wheels mounted beneath the same, a car adapted to run on such track and 15

to pass between such legs and underneath said deck, said car being provided with removable terminally sloping rail-sections adapted to be disposed to engage the wheels mounted beneath said deck and thereby elevate said frame, and means connected with said hoisting mechanism for drawing said car underneath said deck. 30

22. The combination with a frame comprising a deck and legs adapted to support the same over a track, of hoisting mechanism borne by said deck, cross-shafts mounted in said deck, double-flanged wheels mounted on said shafts and extending downwards below said deck, a flat car adapted to run on such track and to pass between such legs and underneath said deck, terminally sloping rail-sections adapted to be removably placed on said car in position to engage said wheels and thereby elevate said frame, a sheave in one end of said frame, a pulley in the opposite end, and a cable operable by said hoisting mechanism and adapted to be optionally passed around said sheave to one end of said car, or around said sheave and 45 said pulley to the other end thereof, whereby said car may be drawn beneath said deck from either end. 40

Signed by me, this 24th day of December, 1906.

JOHN R. McGIFFERT.
